UNITED STATES PATENT OFFICE

1,992,000

DISPLAY APPARATUS

Frank Gillette Carey, Brooklyn, N. Y.

Application November 15, 1933, Serial No. 698,137

6 Claims. (Cl. 40—126)

This invention relates to a new and useful illusion method of advertising merchandise in flowing form, adapted to be arranged in a store window, booth or the like and has for its general object to provide a method which will attract attention, cause comment and excite interest.

Another object of the invention is to provide an illusion apparatus of the character described, especially adapted for use in connection with the advertising and displaying of food products, although the apparatus is capable of various embodiments to adapt it to the particular use for which it may be desired.

Another object of the invention is to provide an advertising display apparatus which is novel in construction and operation, which may be relatively cheaply constructed and economically operated.

A particular feature of the invention is the provision of mechanism, embodying the representation of a container of merchandise, a receiver of merchandise and an inclined chute discharging into the container and leading to the receiver, etc., which when viewed from the front appears to continuously pass merchandise, such as certain food products, from the container into the receiver. Due to its construction the apparatus may be operated at any time, or may be continuously operated if desired.

With the above and other objects in view and the means of their attainment will be more apparent from the following detailed description of an embodiment, illustrated in the accompanying drawing in which:

35 Figure 1 is a perspective view of the invention.

Figure 2 is a vertical cross sectional view taken through the cabinet and looking toward the left, and

40 Figure 3 is a detail plan view showing a means for driving the conveyors.

Referring to the drawing in detail, 1 designates a cabinet structure open at its front and provided with a bottom 2, sides 3 and 4, a back 5 and 45 a top 6. The back portion of the cabinet is provided with a partition wall 7, spaced from the back 5, to provide a rear compartment 8 and the bottom portion is provided with a floor 9, spaced from the bottom 2, to provide a bottom compartment 10. A hanger 11 is located within the open space of the cabinet and is made in the form of a glass bar, having its ends mounted in the opposite side walls 3 and 4. This hanger is arranged in the upper central portion of the cabinet, for mounting at the right side thereof, a box or carton 12, made to represent a container of merchandise. A part 13 representing a receiver of merchandise, is also located within the open space of the cabinet and this receiver is designed 55 to rest upon a stand 14 mounted on the floor 9,

adjacent the side wall 3. The stand supports the receiver in spaced relation to the floor 9 of the cabinet and is preferably made from glass tubing. The receiver 13 may be made in any desired shape but in the present instance is shown made in the shape of a hollow globe, on the outside of which is arranged a map of the world, so as to convey the idea that certain brands of merchandise are used all over the world.

5 Within the cabinet is mounted an inclined 10 trough-like chute 16 which passes through the container 12 and is connected to the receiver 13. This chute is provided for receiving merchandise at its upper end and guiding its passage to and through the container 12 and discharging it 15 into the receiver 13. The chute is secured in position in any suitable manner and comprises a rear portion 17, leading from the upper part of the compartment 8 and passing into the container 12, and a lower portion 18 connecting the container 12 and receiver 13. The lower portion of the chute is preferably made of glass, so that merchandise passing from the container to the receiver may be clearly seen.

To permit the passage of merchandise through 25 the receiver 13, the receiver is provided with a central vertically arranged open ended tube 19, which is in register at its lower end with an outlet opening 20 made in the floor 9 of the cabinet. This opening 20 is surrounded by the stand 30 14, that supports the receiver, and to conceal the opening and the passage of merchandise therethrough, when the cabinet is viewed from the front, a mirror 21 is mounted within the stand 14, in front of the opening 20. The mirror 35 is arranged to reflect the front half of the stand 14, thus giving the effect of a whole stand and thereby providing an illusion.

The merchandise after passing through the receiver 13 falls upon a horizontally arranged conveyor 22 located within the lower compartment 10. This conveyor is of the endless belt type, is carried on suitable rollers 24 and 25 mounted on the bottom 2 of the cabinet and is arranged to convey the merchandise, in the direction shown 45 by the arrow and dump it into a hopper 26 located in the bottom of the compartment 8. From the hopper 26 the merchandise is then picked up and conveyed to the upper end of the chute 16, by a vertically arranged conveyor 27. This 50 conveyor is of the endless type and is provided with a series of scoops or buckets 28, which are arranged to travel, in the direction shown by the arrow and dump the merchandise into the upper, or receiving end of the chute 16. As shown in 55 Figure 2, the end of the chute is provided with a pivoted end or mouth piece 30, for catching the articles of merchandise delivered from the buckets 28. The buckets in their downward movement, come into contact with the mouth 60

piece and force it out of their path of movement, after which it is returned to its upper position by means of the spring 31.

An inclined mirror 33 is also located within the open space of the cabinet and is arranged to snugly fit within the upper rear portion thereof, so that its opposite side edges contact with the inner side walls of the cabinet. The mirror is secured in position, at an angle of 45°, by having its lower edge 34 connected to the back portion of the cross bar 11 and its upper edge 35 secured to the inner edge of the cabinet, where the top 6 and partition wall 7 meet. By connecting the lower edge of the mirror to the rear of the cross bar 11, it is obvious that when the cabinet is viewed from the front, the lower edge of the mirror is completely concealed from view. As shown in the drawing the mirror is located behind the container and is arranged for concealing that portion of the chute leading to the container.

The inner side, back and top walls of the cabinet are provided with any suitable design of symmetrical form, as indicated at 40. As herein shown the design consists of squares, which may be made of contrasting colors if desired. As shown, the squares are so arranged that the side edge of the mirror cuts through the squares at an angle of 45° from corner to corner, thus reflecting one half of the square and forming a whole square and therefore concealing the side edges of the mirror and forming an illusion. The illusion gives the effect of continuous and unbroken surface of adjacent inner sides, back and top wall of the cabinet and makes the container of merchandise appear as though it is suspended in mid air.

Any suitable means may be employed for driving the conveyors. As shown in Figure 3, a suitable motor 36 is provided whose shaft has a worm gear 37, which is in mesh with and drives a similar gear 38, fixed on one end of the lower transverse shaft 27' of the conveyor 27. On the other end of the shaft 27' is mounted a bevel gear 39 which meshes with a bevel gear 40 mounted on the shaft 25' of the conveyor 22. Through the mechanism described, both the conveyors are driven in the direction shown by the arrows.

From the foregoing it is obvious that when the motor is started the conveyors 22 and 27 operate to continuously deliver merchandise, such as certain food products, to the upper end of the chute. After the merchandise enters the chute it then flows downwardly, through the container 12 and then passes to and through the receiver 13 and falls on the belt conveyor 22. Due to the construction and arrangement of the cabinet structure, as above described, merchandise such as rice, tea, etc. will appear to be continually passing in flowing granular form from an apparent receptacle, and therefrom discharging the merchandise into an apparent receiver.

It is obvious that those skilled in the art may vary the details of construction and arrangement of parts without departing from the spirit of my invention, and therefore, I do not wish to be limited to such features, except as may be required by the claims.

What is claimed is:

1. An illusion apparatus of the character described comprising a cabinet structure, a hanger located within the open space of the cabinet, a

part representing a container of merchandise mounted on the hanger, a part representing a receiver of merchandise co-operable with the container, an inclined chute discharging into the container and leading to the receiver, a mirror behind the container for concealing the portion of the chute, leading to the container and means for receiving merchandise from the receiver and discharging it into the upper end of the chute.

2. A illusion equipment of the character described, comprising a cabinet structure, the inner sides, back and top walls thereof arranged with symmetrical designs, a mirror located in the cabinet and disposed at an angle to the direction of normal vision thereof, said mirror giving the effect of continuous and unbroken surface of adjacent sides and top wall of the cabinet and means located within the open space of the cabinet representing a container of merchandise, and a part simulating a receiver co-operable with the part representing the container for the purpose set forth.

3. An illusion equipment of the character described, comprising a cabinet structure, the inner sides, back and top walls thereof arranged with symmetrical designs, a mirror located in the cabinet and disposed at an angle to the direction of normal vision thereof, said mirror giving the effect of continuous and unbroken surface of adjacent sides and top wall of the cabinet, an element simulating a container of merchandise located adjacent the front projecting edge of the mirror, and a part simulating a receiver co-operable with the part representing the container for the purpose set forth.

4. An illusion equipment of the character described, comprising a cabinet structure, the inner sides, back and top walls thereof arranged with symmetrical designs, a mirror located in the cabinet and disposed at an angle to the direction of normal vision thereof, said mirror giving the effect of continuous sides and top wall of the cabinet, an element simulating a container of merchandise located adjacent the front projecting edge of the mirror, means for receiving the merchandise discharged from the container, apparatus for conveying the material from the receiver to the container including a delivery chute, said chute located behind and concealed by the mirror.

5. In combination, a support, a part representing a container of merchandise mounted on the support, a part representing a receiver, an inclined chute discharging into the container and leading to the receiver, a mirror mounted on the support for concealing that portion of the chute leading to the container and means for receiving and conveying merchandise from the receiver and discharging it into the upper end of the chute.

6. In combination, a support, a hanger mounted on the support, a part representing a container of merchandise mounted on the hanger, a part representing a receiver of merchandise co-operable with the container, an inclined chute discharging into the container and leading to the receiver, a mirror mounted on the support for concealing that portion of the chute leading to the container and means for receiving and conveying merchandise from the receiver and discharging it into the upper end of the chute.

FRANK GILLETTE CAREY.
